Joseph P. Farrar, Esq.(57) **ABSTRACT**

An airtight container including a container body having a neck with an opening at one end, a cap having inside a portion having a convex lower end side and attaches to the neck, and a packing. A vertical cross-section of a mouth of the opening forms an upwardly convex curve. The packing has a first concave portion formed on the outer rim of the upper surface, a second concave portion formed on the lower surface sharing a bottom with the first concave portion, and a bent portion radially outboard of the center of the packing and radially inboard of the first and second concave portions are formed, to generate stress that widens the first concave portion and narrows the second concave portion when the cap is attached and the inner surface of the second concave portion is contacted against the mouth of the opening of the neck.

AIRTIGHT CONTAINER

**CROSS-REFERENCE TO RELATED
APPLICATION**

This application claims priority pursuant to 35 USC § 119 from Japanese Patent Application No. 2020-186440, filed on Nov. 9, 2020, the entire contents of which are incorporated herein by reference.

BACKGROUND

Technical Field

The present disclosure relates to an airtight container.

Related Art

A conventional airtight container comprises a container body in which the contents are stored and a cap that seals the opening of the container body via a packing. The airtight container has a cylindrical neck to which the cap is attached, and the top of the neck is open.

In case that the longitudinal axis of the cylindrical neck is set to the vertical direction, and an opening that connects to the storage space of the contents is provided in the top of the neck, then with some airtight containers the shape of the cross-section of the open end of the neck when the neck is cut along a plane that includes the longitudinal axis has an upwardly convex curve. There exist packings for sealing the opening of this type of airtight container (i.e., packings for sealing cans, packings for re-sealable lids) and caps with the packing attached (re-sealable lids, re-sealable lid devices). These conventional packings are disk-shaped, with a concave portion formed around the underside of the disk that is shaped to fit the contour of the curved surface of the open end of the neck. When the cap is attached, the inner surface of this concave portion is configured to fit snugly around the open end.

SUMMARY

Airtightness is required of all airtight containers, such that, when the cap is attached, the contents should not leak if the container is dropped, etc. In the conventional airtight containers, airtightness is ensured by pressing the packing downward when the cap is attached and fitting the concave portion formed in the underside of the packing around the open end of the neck. Further, with some packings an upwardly open concave portion is formed in the top surface of the packing as well in order to increase the downward pressing force.

However, with the conventional airtight container, it may not be possible to maintain sufficient air pressure inside the container body in a reduced-pressure environment such as high elevations or in the cargo compartment of an aircraft. To ensure airtightness under these conditions, it is possible to make the cap attachment structure more complicated or use a larger number of parts, but doing so makes it difficult to provide an airtight container at low cost. Further, such caps are so-called "crown caps", in which the open end of the container body to which the cap is attached (hereinafter sometimes referred to as the "mouth") is limited to the B-type base specified by JIS Z 1607 industrial standard. However, given the wide variety of cap attachment structures, an airtight container versatile enough to support such a wide variety of cap attachment structures is also required.

2

Therefore, present disclosure has as its objective to provide an airtight container that has an uncomplicated structure and can accommodate a wide variety of cap attachment structures while ensuring superior airtightness.

To achieve the above-described objective, one aspect of the present disclosure provides an airtight container having a container body provided with a cylindrical neck having an opening at one end, a cap that is removably attachable to the neck, and a packing that seals the opening. With the longitudinal axis of the cylindrical neck as the vertical direction, the opening opens upward. In a vertical cross-section along a plane including the vertical direction, a mouth of the opening is a curved line that is upwardly convex. The packing has a flattened planar shape with irregular surfaces on both sides, with a groove-shaped first concave portion coaxial with the longitudinal axis formed in the upper surface of the outer rim of the packing, a groove-shaped second concave portion coaxial with the longitudinal axis formed in the lower surface of the outer rim of the packing that shares a bottom with the first concave portion, and a bent portion bent in a groove shape with a bottom toward the bottom formed at a position radially outboard of the center of the packing and radially inboard of an area where the surface of the first concave portion and the second concave portion are formed. An outer edge of the bent portion and an inner edge of the first concave portion share a shared side wall, and the shared side wall has a top that is continuous with a side wall on the inner edge of the first concave portion and generates stress that widens the first concave portion to generate stress that narrows the second concave portion. An inside of the cap has a portion formed therein having a convex shape on a lower end side thereof and disposed coaxial with the longitudinal axis, with the lower end side thereof being formed in a shape of decreasing width toward a tip thereof. When the cap is attached to the neck in a state in which the inner surface of the second concave portion is contacted against the mouth of the opening of the neck, the portion having a convex shape on a lower end side thereof is inserted into the first concave portion and widens the first concave portion.

The cap may be configured by a hollow cylindrical cap body that opens downward and a pressing member that is circular or annular in planar shape disposed within the cap body and arranged with the cylindrical axis direction as its normal, and the pressing member has a protruding circumferential lip having a convex shape on a lower end side around the lower rim thereof. Alternatively, the cap may be configured by a hollow cylindrical cap body that opens downward and a pressing member that is annular in planar shape disposed within the cap body and arranged with the cylindrical axis direction as its normal, with the pressing member having a lower end side that is convex in vertical cross-sectional shape along a plane including the vertical direction.

Further, the cap body can be provided with a tubular protrusion that depends vertically downward from the inside top surface of the cap body, such that the lower end of the tubular protrusion abuts on the upper surface of the pressing member while the cap is attached and presses the pressing member downward.

Preferably, the neck is cylindrical, and the opening, the circumferential protrusion, and the packing have a circular planar shape when viewed from along the vertical direction. More preferably, the cap is a screw-type cap that screws onto a male screw thread formed on the outside of the neck.

EFFECT OF THE DISCLOSURE

According to the present disclosure, an airtight container having an uncomplicated structure and is capable of accom-

modating a wide variety of cap attachment structures while ensuring superior airtightness is provided. Other effects and advantages will become clear from the description that follows.

BRIEF DESCRIPTION OF THE DRAWINGS

FIG. 1A is a perspective view illustrating the appearance of the airtight container according to an embodiment of the present disclosure, with a cap and a packing that are constituent parts of the airtight container removed.

FIG. 1B is a perspective view illustrating the appearance of the airtight container with the cap attached.

FIG. 2 is an exploded perspective view illustrating the configuration of the airtight container, as viewed from above.

FIG. 3 is an exploded perspective view illustrating the configuration of the airtight container, as viewed from below.

FIG. 4 is a cross-sectional view illustrating the structure of the packing that is a constituent part of the airtight container.

FIG. 5A is a cross-sectional view of the entire airtight container, and FIG. 5B is a cross-sectional view of a main part of the airtight container.

FIG. 6A is a cross-sectional view of the entire airtight container, and FIG. 6B is a cross-sectional view of a main part of the airtight container.

FIGS. 7A, 7B are cross-sectional views illustrating the mechanism of operation of the sealing structure of the present embodiment.

FIG. 8 is a cross-sectional view illustrating a thickness of each portion of the packing.

FIGS. 9A, 9B, 9C, 9D are cross-sectional views illustrating sealing structures of airtight containers according to comparative examples.

FIG. 10 is a graph illustrating the relationship between the tightening torque of the cap and the airtightness of the airtight container according to the embodiment of the present disclosure.

FIG. 11A is a perspective view illustrating a modified example of a pressing member that is a constituent part of the airtight container according to the embodiment of the present disclosure, and FIG. 11B is a vertical cross-sectional view of a part of the pressing member.

FIG. 12A is a perspective view illustrating another modified example of a pressing member that is a constituent part of the airtight container according to the embodiment of the present disclosure, and FIG. 12B is a vertical cross-sectional view of a part of the pressing member.

DETAILED DESCRIPTION

An embodiment of the present disclosure will now be described with reference to the accompanying drawings, in which the same or similar parts are designated by the same reference numerals and duplicate description thereof omitted. Parts designated with reference numerals in one drawing may be left undesigned in other drawings if such parts are not essential to the explanation.

FIGS. 1A, 1B are external views of an airtight container (hereinafter also referred to as simply "the container 1") according to an embodiment of the present disclosure. In particular, FIG. 1A illustrates the container 1 in a state in which a cap 3 is detached from a container body 2, whereas FIG. 1B illustrates the container 1 in a state in which the cap 3 is attached to the container body 2. As shown in FIG. 1A,

the container 1 has a container body 2 in which the contents are stored, a bottomed cylindrical cap 3 whose bottom is a top surface 31, and a disk-shaped packing 4.

Cosmetics, for example, may be contained inside the container body 2. The container body 2 is composed of an exterior case 2a and a cup member 2b contained within the exterior case 2a and which is the storage part that actually stores the contents. The exterior case 2a has a structure consisting of a bowl-shaped body portion 22 whose diameter gradually decreases toward a bottom portion 21 and a cylindrical neck 23 of reduced diameter with respect to the body portion 22, formed as a single integrated unit with the body portion 22 via a shoulder 27, so that the body 22 and the neck 23 are coaxial. Taking the longitudinal axis 100 of the neck 23 (hereinafter also referred to as "the cylindrical axis 100" or simply "the axis 100") as the vertical direction, the container body 2 is open upward, the upper end of the cup member 2b protrudes above the upper end of the neck 23, and the upper edge of the area protruding above the neck 23 is the mouth 24 of the container body 2.

The cap 3 of the container 1 according to the embodiment is a so-called screw-type cap, in which a male screw thread 25 is formed around the outside of the neck 23 and a female screw thread 33 that engages this male screw thread 25 is formed around the inside surface of the cap 3. As shown in FIG. 1B, when the cap 3 is screwed onto the neck 23, the cap 3 is attached to the container body 2 and the mouth 24 fits snugly against the bottom edge of the packing 4, thus sealing the container body 2. The container 1 according to the embodiment is characterized by the structure of the cap 3 and the packing 4, which ensures superior airtightness when the cap 3 is attached.

Configuration of the Airtight Container

FIGS. 2 and 3 are exploded perspective views illustrating the configuration of the container 1, with FIG. 2 being a perspective view of the container 1 as viewed from above and FIG. 3 is a perspective view of the container 1 as viewed from below. In FIGS. 2 and 3 the container body 2 and cap 3 are shown in an exploded perspective view. In addition, FIG. 2 also provides enlarged views of parts of the container 1 corresponding to the circled areas (101, 102, and 103). In the enlarged views of each of these parts, the vertical cross-section of the container 1 along a plane including the axis 100 is shown.

As shown in FIGS. 2 and 3, the container body 2 is composed of an exterior case 2a and a cup member 2b. The exterior case 2a and the cup member 2b are molded products made of a hard plastic, such as polyketone (POK), polyoxymethylene (POM), ABS, polyethylene (PE), polypropylene (PP), polyethylene terephthalate (PET), acrylonitrile styrene (AS), or polymethyl methacrylate (PMMA). The exterior case 2a has a cylindrical space 26 that maintains the shape of the opening of the neck 23 and is continuous with the interior of the body portion 22 of the case 2a. The container body 2 is configured by accommodating the cup member 2b in this space 26. It is to be noted that the cup member 2b may be configured so as to be either detachable from the exterior case 2a or fixedly mounted to the exterior case 2a once it is attached thereto.

The cup member 2b is a hollow cylinder with a bottom, with the area on the upper end side expanding radially outward so as to form a thickened rim. The lower end side of this thickened rim abuts on the upper end surface of the neck 23. As a result, when the cup member 2b is accommodated within the exterior case 2a, the upper end side of

the above-described thickened rim of the cup member 2b protrudes above the top of the neck 23 and forms the mouth 24. The mouth 24 has an upwardly convex curved shape. That is, as shown in the enlarged view of area 103 in FIG. 2, the vertical cross-section when along the plane including the axis 100 has an upwardly convex curved shape. Note that the container body 2 need not be composed of an exterior case 2a and a cup member 2b as described herein. Thus, the interior of the exterior case 2a may form the storage space for the contents, and the exterior case 2a may be the container body 2. In any case, it suffices if the mouth 24 has an upwardly convex curved shape.

The cap 3 is composed of a bottomed cylindrical cap body 3a having a top surface 31 and opening downward, and a disk-shaped pressing member 3b coaxially disposed within the cap body 3a. The cap body 3a and the disk-shaped pressing member 3b may be made of a thermoplastic resin such as POK, POM, ABS, PE, PP, PET, AS, polyester or ionomer.

As shown in FIG. 3, a female screw thread 33 that engages the male screw thread 25 of the neck 23 is formed in the inside surface 32 of the cap body 3a. A tubular protrusion 34 that depends downward from the center of the bottom of the top surface 31 is formed in the cap body 3a. As shown in FIG. 2, a circular concave portion 35 is formed in the center of the upper surface of the disk-shaped pressing member 3b. The disk-shaped pressing member 3b has a normal axis along the cylindrical axis 100 and is disposed in the cap body 3a in a state in which the lower end of the tubular protrusion 34 is in contact with the bottom of the concave portion 35. The disk-shaped pressing member 3b may be fixed to the cap body 3a by a method such as adhesion or fitting, or it may be detachably attached to the cap body 3a.

An annular projection 36, projecting downward and concentric with the axis 100, is formed around the lower rim of the disk-shaped pressing member 3b. As can be seen in the vertical cross-section of the annular projection 36 shown in the enlarged view of area 101 in FIG. 2, the annular projection 36 has a triangular shape with its apex at the bottom and widens radially inward and outward at its base toward the top. When the cap 3 is mounted on the neck 23 of the container body 2, the disk-shaped pressing member 3b contacts the upper surface of the packing 4 and presses the packing 4 downward. Hereinafter, the disk-shaped pressing member 3b is referred to as a pressing member 3b, and the annular projection 36 formed around the lower rim of the pressing member 3b is referred to as a circumferential lip 36.

The packing 4 is a unitary molded product made of a flexible material such as polyethylene (PE), polypropylene (PP), polyethylene terephthalate (PET) or other plastic, or an elastic material such as an elastomer, NBR, IIR, natural rubber, fluororubber, etc. FIG. 4 shows a vertical cross-sectional view of the packing 4. As shown in FIGS. 2-4, the packing 4 is a disk with irregular surfaces. As shown in the enlarged view of the area 102 in FIG. 2 and in FIG. 4, two annular protrusions (41i, 41o) concentric with the axis 100 are formed around the edge of the upper surface of the packing 4. As a result, a U-shaped concave portion 42a is formed in the upper surface of the outer edge of the packing 4. Hereinafter, the concave portion 42a is referred to as the first concave portion 42a, and the protrusions (41i, 41o) on the inner edge and the outer edge that together form the first concave portion 42a are referred to as the upper surface inner protrusion 41i and the upper surface outer protrusion 41o, respectively.

The packing 4 maintains a generally flat shape radially outward from the center until reaching an area bent sharply into the shape of a U from where the first concave portion 42a is formed. Thereafter, heading radially outward further from the area where the first concave portion 42a is formed, an edge portion 44 that bends downward is formed. Further, a protrusion 45o that protrudes downward is formed on the lower surface of the packing 4 between the above-described sharply bent area (hereinafter also referred to as the bent portion 43) and the edge portion 44. As a result, an inverted U-shaped concave portion 42b that shares a bottom 46 with the first concave portion 42a is formed by an outer wall 45i of the bent portion 43 and the protrusion 45o. In the packing 4 of the container 1 according to the embodiment, the upper end of the wall 45i is continuous with the upper surface inner protrusion 41i.

Hereinafter, the area from the center of the packing 4 to the bent portion 43 is referred to as flat portion 47, and the inverted U-shaped concave portion 42b formed in the bottom of the outer edge of the lower surface of the packing 4 is referred to as the second concave portion 42b. The protrusion 45o on the outer edge forming the second concave portion 42b (together with the outer wall 45i of the bent portion 43) is referred to as the lower surface outer protrusion 45o, and the wall 45i shared by the bent portion 43 and the second concave portion 42b is referred to as the shared wall 45i.

As shown in FIGS. 2 to 4, the packing 4 is similar to ordinary disk-shaped packing, with concavities and convexities formed in various places for the purpose of reinforcing or dispersing stress when pressed downward. For example, as illustrated in FIG. 3, radiating ribs 48 are formed on the lower surface of the flat portion 47 and an annular convex portion 49 is formed in the center of the upper surface of the flat portion 47. Further, in this embodiment, as shown in the enlarged view of the area 102 in FIG. 2 and in FIG. 4, a thick portion 50 of enhanced thickness protruding radially inward is formed on the inside of the inner wall of the bent portion 43.

Sealing Structure

In the container 1 having the above-described configuration, when the cap 3 is attached to the container body 2, while the second concave portion 42b of the packing 4 is contacted against the mouth 24 the cap 3 is screwed onto the neck 23. As a result, the packing 4 is squeezed between the mouth 24 and the pressing member 3b to put the container body 2 into an airtight state. FIGS. 5A-6B explain the container sealing structure. FIGS. 5A and 5B are vertical cross-sectional views of the container 1 when the container body 2 is not sealed, and FIGS. 6A, 6B illustrate are vertical cross-sectional view of the container 1 when it is in a sealed state. In addition, FIGS. 5A and 6A are vertical cross-sectional views of the entire container 1, whereas FIGS. 5B and 6B are enlarged views of the area inside the circle 104 in FIG. 5A and the area inside the circle 105 in FIG. 6A, respectively.

As described above, the cap 3 is a screw-type cap, such that, when the cap 3 is attached to the container body 2, as shown in FIG. 5A the packing 4 is placed on the mouth 24 of the cup member 2b and the cap 3 covers the neck 23. At this time, the mouth 24 of the cup member 2b is opposite the second concave portion 42b of the packing 4 and the circumferential lip 36 of the pressing member 3b is opposite the first concave portion 42a of the packing 4. Note that with the cap 3 just covering the neck 23, the lower end of the cap

3 is separated upward from the shoulder portion 27 of the exterior case 2a of the container body 2. Further, as shown in FIG. 5B, the packing 4 is not pressed downward by the pressing member 3b but remains placed on the mouth 24 while maintaining its original shape.

Next, as shown in FIG. 6A, once the cap 3 is screwed onto the neck 23 to a predetermined closing position, as shown in FIG. 6B the circumferential lip 36 that widens upward enters the first concave portion 42a and pushes apart the upper surface inner protrusion 41i and the upper surface outer protrusion 41o of the first concave portion 42a, thus widening the gap between them while concomitantly forcing the shared wall 45i and the lower surface outer protrusion 45o closer together. As a result, the second concave portion 42b is more firmly attached to the mouth 24 in conjunction with the widening of the first concave portion 42a as described above, thereby further enhancing the airtightness of the container body 2.

FIGS. 7A, 7B are cross-sectional views illustrating in detail the mechanism of operation of the sealing structure of the container 1. FIGS. 7A, 7B illustrate the relation between the operation of widening the first concave portion 42a with the pressing member 3b and the operation of more strongly attaching the second concave portion 42b to the mouth 24, while omitting for ease of illustration the configuration of the container 1 excluding the pressing member 3b and the packing 4. Thus, FIG. 7A shows the shape of the packing 4 before the cap 3 is attached and FIG. 7B shows the deformation of the packing 4 due to attaching the cap 3. As shown in FIG. 7A, in the state before the cap 3 is completely attached, although the circumferential lip 36 of the pressing member 3b is inside the first concave portion 42a the packing 4 still retains its original shape. In contrast, as shown in FIG. 7B, when the screw-type cap 3 is further screwed onto the neck 23 the circumferential lip 36 is pressed into the first concave portion 42a and presses down on the packing 4. The upper end side of the circumferential lip 36 has a width wider than the distance between the upper surface inner protrusion 41i and the upper surface outer protrusion 41o of the first concave portion 42a, such that, as illustrated by the black arrows in FIG. 7B, as the deposited lip 36 presses down on the packing 4 downward it spreads apart the upper surface inner protrusion 41i and the upper surface outer protrusion 41o of the first concave portion 42a by bending them radially inward and outward respectively, so that the first concave portion 42a widens.

When the first concave portion 42a is widened from its original shape, upward stress is generated in both the walled portion 45i and the lower surface outer protrusion 45o as illustrated by the white arrows in FIG. 7B, and that stress squeezes the second concave portion 42b by pushing the walled portion 45i and the lower surface outer protrusion 45o closer together as shown by the arrows with hatching in FIG. 7B. At this time, as long as the mouth 24 is in contact with inner surface of the second concave portion 42b, the stress that is attempting to deform the second concave portion 42b becomes a force that sandwiches the mouth 24 from both radially inside and outside. As a result, the mouth 24 is squeezed by and firmly attaches to the outer surface of the shared wall 45i and the inner surface of the lower surface outer protrusion 45o of the second concave portion 42b, and the airtightness of the container body 2 is enhanced. It is to be noted that, in the container 1 according to the embodiment, the thickness of each part of the packing 4 is adjusted in order to deform the second concave portion 42b with the deformation of the first concave portion 42a.

FIG. 8 shows an example of the thickness of each part of the packing 4. In the container 1 according to the embodiment, the bent portion 43 has a thickness $t1=0.3$ mm at the bottom, a thickness $t2=0.6$ mm at the top of the shared wall 5 45i, and a thickness $t3=0.4$ mm of the bottom 46 shared by the first concave portion 42a and the second concave portion 42b. Note that the thickness of each part of the packing 4 is not limited to those of the example shown in FIG. 8, and may be adjusted as appropriate depending on the diameter of the 10 packing 4, the tightening torque of cap 3 at the time of packaging, the required airtightness, etc. In any case, it suffices if the first concave portion 42a and the second concave portion 42b are formed by sharing the bottom 46 on the 15 upper surface and the lower surface of the outer edge of the packing 4, and if the bent portion 43 is formed somewhere between the center of the packing 4 and the area where the first concave portion 42a and the second concave portion 42b are formed. In addition, it suffices if the bent portion 43 bends downward in the radially outward direction and then bends upward to form the shared wall 45i, and the upper end of the shared wall 45i is continuous with the upper surface inner protrusion 41i of the first concave portion 42a.

The vertical cross-sectional shape of the first concave portion 42a and the second concave portion 42b is not limited to a V-shaped, inverted V-shaped, or U-shaped or 25 inverted U-shaped cross-section. Similarly, the bent portion 43 is also not limited to the U-shape.

Airtightness

30 Next, in order to evaluate the airtightness performance of the container 1 according to the embodiment, four types of containers with sealing structures different from the sealing structure of the container 1 according to the embodiment 35 were prepared as comparative examples. FIGS. 9A, 9B, 9C, 9D are cross-sectional views illustrating sealing structures of airtight containers prepared as these comparative examples. That which is illustrated in FIGS. 9A, 9B, 9C, 9D corresponds to the area within the circle 104 in FIG. 5A. Further, 40 in FIGS. 9A, 9B, 9C, 9D, the cap body 3a and the exterior case 2a are omitted, and the pressing member 3c, the packing 4 and cup member 2b are shown only in cross-section. The configurations of the container body 2 and the cap body 3a of the containers 1a-1d according to the 45 comparative examples is the same as that of the embodiment. A decompression test was conducted on the container 1 according to the embodiment and the containers 1a-1d according to the comparative examples shown in FIGS. 9A, 9B, 9C, 9D, in which each container (1, 1a-1d) was placed in a decompression environment after the cap 3 was attached and the opening of the container body 2 was closed, and the air pressure at which the contents in the container body 2 leaked was measured.

50 As shown in FIGS. 9A-9D, no circumferential lip 36 is formed on pressing members 3c of the containers 1a-1d according to the comparative examples. Further, although the containers 1a-1d have the same packing 4 as that of the container 1 according to the embodiment, in FIGS. 9B-9D the parts indicated by the diagonal hatching are filled with adhesive in a cured state so that they cannot be elastically deformed.

55 In the decompression test was performed on the container 1 according to the example and the containers 1a-1d according to the comparative examples, the container 1a and the container 1d maintained their airtightness up to an atmospheric pressure of 350 hPa. However, the contents of the container 1b and the container 1c leaked before the pressure

was reduced to 350 hPa. In contrast, the container 1 according to the embodiment maintained its airtightness until the pressure was reduced to the extremely low pressure of 80 hPa. Considering that standard atmospheric pressure is 1013 hPa, although it could be said that the container 1a and the container 1d exhibited sufficient airtightness performance, the container 1 according to the embodiment proved capable of maintain airtightness at extremely low atmospheric pressures of 1/4 or less that of the containers 1a and 1d.

Considering the results of decompression tests on various containers (1, 1a-1d), first, from the test results of the containers 1a-1d, it was clear that it is necessary for the bent portion 43 to be able to elastically deform in order to ensure sufficient airtightness. In other words, it was clear that it is necessary that a bent portion 43 be formed in the packing 4. From the test results of the container 1 according to the embodiment it was clear that superior airtightness can be provided by the bent portion 43 and the first concave portion 42a elastically deforming, and by the circumferential lip 36 of the pressing member 3b forcibly widening the first concave portion 42a.

Other Embodiments

Although the cap 3 of the container 1 according to the embodiment is composed of a cap body 3a and a pressing member 3b provided with a circumferential lip 36, alternatively the protruding lip 36 may be integrated into the inside of the top surface 31 of the cap body 3a. With such a configuration, the pressing member 3b becomes unnecessary and the number of parts to be used to configure the container 1 can be reduced. If the circumferential lip 36 is integrated into the cap body 3a, it is desirable that the shape of the top surface 31 of the cap body 3a is flat on the inside so as to fully contact the flat portion 47 of the packing 4. On the other hand, if the cap 3 is provided with the pressing member 3b is, it is not necessary to flatten the inside of the top surface 31, and if a structure for holding the member 3b is provided inside the cap body 3a the external shape of the cap body 3a can be designed more freely. In any case, whether or not to include the pressing member 3b can be decided as appropriate depending on the appearance of the container 1 and the like.

When the container 1 is provided with the screw-type cap 3 and the pressing member 3b, a slight amount of play may be provided between the outer edge of the pressing member 3b and the inside surface 32 of the cap body 3a, so that, in the process of screwing the cap body 3a, as friction between the circumferential lip 36 and the first concave portion 42a increases, the cap body 3a and the pressing member 3b rotate relatively around the axis 100 and the cap 3 can be attached to the neck 23 more smoothly.

Although the container 1 according to the embodiment is provided with the screw-type cap 3, alternatively the cap 3 attachment structure may, for example, be one in which a hook formed in the cap body 3a disengagingly engages a concave portion formed in the outside of the neck 23. Provided that the container 1 according to the embodiment has a sealing structure composed of the packing 4 having the first concave portion 42a, the second concave portion 42b, and the bent portion 43, and the circumferential lip 36 that is squeezed into the first concave portion 42a to widen the first concave portion 42a, that sealing structure may be anything that is universally applicable to any cap 3 attachment structure no matter what it is.

In the container 1, when the pressure inside the container body 2 is relatively high on the cap 3 under a reduced-

pressure environment or the like, a mechanism to hold down the packing 4 that tries to be pushed upward is required. In the attachment structure of the cap 3 using the hook or the like described above, the cap 3 may become disengaged from the neck 23 if the pressure difference between the inside of the container body 2 and the outside is too great. However, the container 1 according to the above-described embodiment uses the screw-type cap 3, and therefore the state of attachment can be maintained as long as the cap body 3a and the like are not damaged.

Furthermore, if the cap 3 is a screw-type cap, the airtightness can be adjusted according to the tightening torque. Therefore, the airtightness of the container 1 can be flexibly set according to the application without the need to change the shape of the packing 4 or the mouth 24 of the container body 2. For example, simply by preparing various container bodies 2 and cap bodies 3a with different screwing amounts, the pressing member 3b and the packing 4 can continue to be used for ordinary purposes. Therefore, when designing different containers 1, it is not necessary to change the shape of the mouth 24 of the container body 2, and as a result it is possible to hold down design costs. FIG. 10 shows the relation between tightening torque and airtightness of the cap 3 of the container 1 according to the embodiment. As is clear from FIG. 10, the airtightness increases as the tightening torque increases.

The flat portion 47 of the flexible packing 4 tries to deform upward in a reduced-pressure environment, and the pressing member 3b abuts on the flat portion 47 to suppress the deformation of the packing 4. However, when the pressure inside the container body 2 is much greater than the atmospheric pressure outside, a thin pressing member 3b may itself be deformed. Therefore, in the container 1 according to the above-described embodiment, a tubular protrusion 34 that depends from the top surface 31 is provided inside the cap body 3a, and as shown in FIGS. 5A-6B the lower end of the tubular protrusion 34 contacts the bottom of the central concave portion 35 in the upper surface of the pressing member 3b to prevent the pressing member 3b from bulging upward. As a result, even if the container 1 is intended for use in a place where the atmospheric pressure is extremely low, it is not necessary to increase the strength of the pressing member 3b by increasing its thickness.

Alternatively, the packing 4 and the cap 3 need not be separate parts, and thus, for example, a projection that supports the edge of the packing 4 may be formed around the inside surface 32 of the cap body 3a. Similarly, the packing 4 may be attached to the lower surface of the pressing member 3b by a method such as adhesion. In any case, as long as the elastic deformation of the bent portion 43, the first concave portion 42a, and the second concave portion 42b of the packing 4 is not inhibited when the pressing member 3b is pressed downward, the packing 4 may be either integrated into the cap 3 or it may be a separate member.

Instead of the planar shape, the pressing member 3b may be an annular shape with an open center. In addition, the planar shape of the ring-shaped pressing member 3b does not have to be flat; that is, the vertical cross-sectional shape may be a shape other than a rectangle. For example, if the pressing member 3b itself is an annular body (O-ring, torus), the planar shape is annular and the vertical cross-sectional shape is circular. Of course, even if the planar shape is annular, the vertical cross-sectional shape is not limited to a circle. FIGS. 11A-12B show examples of the pressing member 3b, having a center hole 37, and although the planar shape is an annular shape the vertical cross-section is not a

11

circle. In a pressing member $3d$ shown in FIGS. 11A-11B, although the planar shape is annular as shown in FIG. 11A, as shown in FIG. 11B, the vertical cross-section (cross-section along the perspective plane a-a in FIG. 11A) is U-shaped. In addition, in the pressing member $3e$ shown in FIG. 12A-12B, although the planar shape is annular as shown in FIG. 12A, as shown in FIG. 12B the shape of the vertical cross-section (cross-section along the perspective plane b-b in FIG. 12A) is an inverted trapezoid with the bottom as the upper base. It suffices if the pressing members ($3b$, $3d$, $3e$) have flattened upper and lower surfaces regardless of the presence or absence of the center hole 37 and the vertical cross-sectional shape.

It is to be noted that the shape of the pressing member ($3d$, $3e$) shown in FIGS. 11A-12B itself functions in the same manner as the circumferential lip 36 . In any case, it suffices if the bottom edge of the pressing member ($3b$, $3d$, $3e$) has a portion (36 , $36b$) that is inserted into the first concave portion $42a$, and that the portion (36 , $36b$) has a vertical cross-sectional shape that narrows toward the lower end, that is, if the bottom of the pressing member ($3b$, $3d$, $3e$) has a portion having a downwardly convex shape. Moreover, the upper end of this portion (36 , $36b$) does not necessarily have to be wider than the lower end. In the pressing member ($3b$, $3d$, $3e$), as for the vertical cross-sectional shape of the circumferential lip 36 of the planar pressing member $3b$, and the vertical cross-sectional shape of the portion $36b$ having the same function as the circumferential lip 36 of the annular pressing member $3b$, polygons of five sides or more and rhombuses with the lower end side as the top are also conceivable. In short, it suffices if the portion (36 , $36b$) that is pressed into the first concave by the force of the pressing member ($3b$, $3d$, $3e$) being pressed downward by the cap body $3a$ is configured to spread apart the first concave portion $42a$ of the packing 4 radially inward and outward so that the second concave portion $42b$ is pressed firmly against the mouth 24 . Note that if the planar shape of the pressing member $3b$ is annular, and the tubular protrusion 34 is formed in the cap body $3a$, as a matter of course the lower end of the tubular protrusion 34 comes into contact with a position on the upper surface of the pressing member $3b$ where the center hole 37 is not formed.

In the container 1 according to the above-described embodiment, the container body 2 and cap 3 have been configured to be disposed coaxial with the longitudinal axis 100 when the cap 3 is attached to the container body 2 . Alternatively, provided that the neck 23 is cylindrical, the neck 23 it may be formed so as to project in any appropriate direction such as an oblique direction with respect to the container body 2 , so long as the longitudinal axis 100 direction of the cap 3 attached to the neck 23 is the vertical direction. Further, the shape of the body portion 22 of the container body 2 is not limited to that of a bowl, and may be any shape such as a square cylinder, a cylinder, or a sphere. Similarly, the external shape of the cap body $3a$ is not limited to that of a cylinder.

Depending on the external design of the container 1 or the design of the attachment structure of the cap 3 , the planar shape of the opening (mouth 24) of the container body 2 does not have to be circular, and the planar shape of the pressing member $3b$ and the packing 4 may be suitably varied according to the shape of the mouth 24 . For example, if the planar shape of the mouth 24 is a rectangle, then the outer shape of the packing 4 is also a rectangle. In any case, when the shape of the opening of the container body 2 is the same, it is clear that the airtightness of the container 1 can be enhanced by utilizing the pressing member $3b$ having the

12

circumferential lip 36 and the packing 4 having the first concave portion $42a$, the second concave portion $42b$, and the bent portion 43 .

Of course, if the shape of the opening of the container body 2 is circular, the planar shape of the pressing member $3b$ is circular or annular, and the planar shape of the packing 4 is circular, then the internal pressure inside the container body 2 is uniformly applied to the packing 4 from the opening and the circumferential lip 36 of the pressing member $3b$ can uniformly deform the first concave portion $42a$ of the packing 4 against this internal pressure. As a result, the airtightness of the container body 2 can be ensured even in extremely harsh reduced-pressure environments.

In the above-described embodiment, the vertical cross-sectional shape of the circumferential lip 36 of the pressing member $3b$ is a V, wide at the top and gradually narrowing toward the bottom. However, the protruding lip 36 may be any shape that, when pressed into the first concave portion $42a$, spreads apart the upper surface inner protrusion $41i$ and the upper surface outer protrusion $41o$ forming the first concave portion $42a$ radially inward and outward. The vertical cross-sectional shape of the circumferential lip 36 may be, for example, a U or an inverted trapezoid. Alternatively, the circumferential lip 36 may have an O-ring-like appearance, and therefore may be circular or ring-shaped in vertical cross-section.

In the container 1 according to the above-described embodiment, the exterior case $2a$, the cup member $2b$, the cap body $3a$, and the pressing member $3b$ are molded plastic products. Alternatively, however, any or all of these members ($2a$, $2b$, $3a$, $3b$) are not limited to plastic, and may be made metal, glass, or some other material. In addition, the exterior case $2a$, cup member $2b$, cap body $3a$, and pressing member $3b$, for example, may be composed of different materials depending on the part.

Further, the pressing member $3b$ may be made of an elastic material. The pressing member $3b$ may, for example, be composed of a material harder than the material of the packing 4 , so long as it can press the packing 4 and cause the packing 4 to deform. Moreover, the pressing member $3b$ should be designed so that, if subjected to a pressing force, it can return to its original shape once that force is released.

What is claimed is:

1. An airtight container comprising:
 a container body provided with a cylindrical neck having
 an opening at one end;
 a cap that is removably attachable to the neck; and
 a packing that seals the opening, wherein
 with a longitudinal axis of the cylindrical neck as the
 vertical direction, the opening opens upward,
 a mouth of the opening is a curved line that is upwardly
 convex in a vertical cross-section along a plane
 including the vertical direction,
 the packing has a flattened planar shape in which are
 formed a groove-shaped first concave portion
 coaxial with the longitudinal axis formed in the
 upper surface of the outer rim of the packing, a
 groove-shaped second concave portion coaxial with
 the longitudinal axis formed in the lower surface of
 the outer rim of the packing that shares a bottom with
 the first concave portion, and a downwardly convex
 bent portion bent so as to form an upwardly open
 groove and formed at a position radially outboard of
 a center of the packing and radially inboard of the
 first concave portion and the second concave portion,
 an outer edge of the bent portion shares a shared side
 wall with an inward facing edge of the first concave
 portion, and the shared side wall has a top that is
 continuous with a side wall on the inward facing
 edge of the first concave portion and generates stress
 that widens the first concave portion to generate
 stress that narrows the second concave portion,
 an inside of the cap has a portion formed therein having
 a convex shape on a lower end side thereof and
 disposed coaxial with the longitudinal axis, the lower
 end side being formed in a shape of decreasing width
 toward a tip thereof,

14

wherein, when the cap is attached to the neck in a state
 in which the inner surface of the second concave
 portion is contacted against the mouth of the opening
 of the neck, the portion having a convex shape on a
 lower end side of the cap is inserted into the first
 concave portion and widens the first concave portion.

2. The airtight container according to claim 1, wherein the
 cap is configured by a hollow cylindrical cap body that
 opens downward and a pressing member that is circular or
 annular in planar shape disposed within the cap body and
 arranged substantially at right angles to the cylindrical axis
 of the cap body, and

15 the pressing member has a protruding circumferential lip
 having the convex shape on a lower end side around the
 lower rim thereof.

3. The airtight container according to claim 1, wherein the
 cap is configured by a hollow cylindrical cap body that
 opens downward and a pressing member annular in planar
 shape disposed within the cap body and arranged substan-
 tially at right angles to the cylindrical axis of the cap body,
 and

25 the pressing member has a lower end side that is the
 convex shape in vertical cross-section along a plane
 including the vertical direction.

4. The airtight container according to claim 2, wherein the
 cap body is provided with a tubular protrusion portion that
 depends vertically downward from the inside top surface of
 the cap body, and

30 the lower end of the tubular protrusion abuts on the upper
 surface of the pressing member while the cap is
 attached and presses the pressing member downward.

5. The airtight container according to claim 1, wherein the
 cap is a screw-type cap that screws into a male screw thread
 formed on the outside of the neck.
